UNITED STATES PATENT OFFICE

STEPHEN O. DOUGHERTY, OF TORONTO, OHIO

WASHING MACHINE

Application filed February 6, 1929. Serial No. 337,968.

This invention relates to laundry apparatus, and more particularly to a machine designed for domestic use for cleaning clothes, draperies, bed wear and analogous articles required to be washed.

The invention provides a machine which is portable and adapted to be driven mechanically, and which admits of ready access to every part for cleaning, repairs, adjustment, or other purpose, the operating parts being housed and protected.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which:—

25 Figure 1 is a perspective view of a washing machine embodying the invention.

Figure 2 is an enlarged vertical, central sectional view of the complete machine on the line 2—2 of Figure 3 looking in the direction indicated by the arrows.

Figure 3 is a horizontal sectional view on the line 3—3 of Figure 2 looking downwardly as designated by the arrows.

Figure 4 is a detail perspective view of the 35 agitator.

Corresponding and like parts are referred to in the following description and designated in the several views of the drawings by like reference characters.

40 The machine is mounted upon legs 1 which are supplied with suitable casters to facilitate movement of the machine from one place to another. The numeral 2 designates the frame or body of the machine and consists of a shell or casing. A compartment 3 is formed in the lower portion of the casing and receives the operating mechanism which is housed and protected thereby. Access to 45 the compartment 3 is had through an open-

ing in a side of the casing which is normally closed by means of a door 5.

A tub 6 is secured within the upper portion of the frame or casing and its bottom is depressed, as indicated at 7. A tube 8 rises 55 centrally from the depressed bottom portion 7 of the tub and terminates a short distance from a plane touching the top of the tub. A shaft 9 extends through the tube 8 and is stepped at its lower end in the bottom of the 60 frame or casing 2. The shaft 9 is tubular and provides means for holding and conveying oil to the lower bearing. The shaft 9 is open throughout and its top portion is square, or of non-circular formation to insure rotation of the agitator in a manner explained more fully hereinafter.

A top 10 is secured to the upper portion of the casing 2 and tub 6 and is depressed, the outer portion extending upwardly and 70 retrorsely bent to embrace the edge portions of the tub and casing. A cover 11 closes an opening formed in the top 10. By having the top depressed drippings are caught and directed back into the tub.

75 The agitator comprises a base 12 of circular outline and inclined outwardly and downwardly from a central point. Ribs 13 are provided upon the upper side of the base 12 and have an approximate radial arrangement. A tube 14 projects upwardly from the base 12 and is of a size to slip over the upper portion of the tube 8 about which it is free to rotate. Wings 15 project outwardly from the tube 14 and provide supplemental agitating elements. A disk 16 is fast to the upper portion of the tube 14 and the upper ends of the wings 15 are connected thereto in any determinate way. Other wings 17 above the disk 16 are attached thereto and to the sides 80 of the tube 14. The outer edges of the wings 17 incline upwardly and inwardly, whereas the outer edges of the wings 15 curve inwardly between their ends. A stud 18 depending from the upper closed end of the tube 14 enters the upper end of the shaft 9 and provides interengaging means to cause the agitator and shaft to rotate in unison. The base portion 12 of the agitator enters the top 85 portion of the depression 7 and comes about 90

flush with the bottom of the tub. The agitator is readily removable and replaceable.

A wringer 19 of any approved construction is mounted at one side of the machine to swing laterally towards or away therefrom. The wringer shaft 20 is mounted in a housing 21 at one side of the casing 2 and a train of gearing connects it with a motor 22 located within the compartment 3.

The train of gearing includes a shaft 23, to which power may be applied from any suitable source, as a motor 22. The motor 22 may be of any type and connected directly to the shaft 23, or indirectly through a belt and pulleys in any determinate way. The shaft 23 is connected to a shaft 26 by suitable gearing which as shown is of the worm type. An arm 27 fast to the shaft 26 is connected by means of a pitman 28 to an arm 29 fast to the shaft 9. This constitutes a single drive. Obviously a double drive may be employed if desired. Suitable gearing forms connecting means between the shaft 26 and the wringer shaft 20. The arm 29 is of greater length than the arm 27 and in consequence rotation of the shaft 26 results in an oscillatory movement being imparted to the shaft 9 and a corresponding movement to the agitator by reason of the connecting means between the agitator and the shaft 9. It is to be understood that the usual clutch, not shown, is provided between the wringer mechanism and the shaft 20 and between the shaft 26 and the shaft 9 to admit of throwing the wringer and the agitator into or out of action in the accustomed way as occasion may require.

The articles to be washed are introduced into the tub 6 and removed therefrom through the opening closed by means of the cover 11. The agitator may be placed within the tub or removed therefrom through the opening which is normally closed by means of the cover 11. The motor 22 may be electric or of any type and when in operation imparts an oscillatory movement to the agitator through the connections illustrated in the accompanying drawings and described more particularly herein.

The construction is such that it can be successfully used for washing fruit and vegetables, and when thus used the wringer mechanism may be eliminated.

Having thus described the invention, I claim:

1. A washing machine including a casing having a bearing upon its bottom, a tub therein having a depressed bottom, a tube projecting vertically from the center of the depressed bottom and terminating adjacent the top of the tub, a tubular shaft within the tube and having its lower end journaled in the bearing, an agitator mounted upon the said tube and interengaging means between the agitator and shaft.

2. A washing machine agitator comprising upper and lower disk elements having an outer and downward inclination from a central point, a tube connecting the disks, ribs disposed upon the top side of the lower disk and having an approximate radial arrangement, and outwardly disposed wings connected at their ends to the said disks, and at their inner edges to the tube.

3. A washing machine comprising a tub, a tube within the tub, a tubular shaft within the tube, an agitator including a tube closed at its upper end and adapted to be slipped upon the first-named tube, and a stud depending from the closed end of the agitator tube for detachable interlocking engagement in the upper end of the shaft.

4. A washing machine comprising a supporting frame, a tub thereon, a tube rising from the center of the tub and terminating adjacent the top thereof, a tubular shaft within the tube and stepped in the frame at its lower end, operating means on the frame connected with the lower end portion of the shaft below the tub, an agitator including a tube rotatably mounted upon the tube rising from the center of the tub and closing the upper end thereof, and interengaging means between the upper ends of the tubular shaft and the tube of the agitator to insure rotation of the latter.

In testimony whereof I affix my signature.
STEPHEN O. DOUGHERTY.
